CLAIM

The ornamental design for a rucksack for seating, as shown and described.

DESCRIPTION

FIG. 1 is a front perspective view of a rucksack for seating showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines shown in the Figures form no part of the claimed design.
